UNITED STATES PATENT OFFICE

2,130,796

GAS VALVE

John H. Grayson, Lynwood, Calif., assignor to
 Grayson Heat Control, Inc., Lynwood, Calif., a
 corporation of California

Original application November 2, 1935, Serial No.
 47,945. Divided and this application May 20,
 1936, Serial No. 80,759

5 Claims. (Cl. 251—46)

This invention relates to valves generally and has particular reference to an improved valve construction especially designed for use in a graduating type oven heat regulator to regulate the flow of gas to an oven burner to maintain a predetermined oven temperature.

One of the principal objects of my invention is to provide a valve in which the poppet type valve disk is universally adjustable on its stem by virtue of a ball and socket mounting, whereby to permit the valve to adapt itself to the valve seat instead of relying upon accurate relationship of the valve stem to the seat for accurate parallel closing and opening movements of the valve disk relative to the seat.

Another important object consists in the provision of an annular oil groove around the valve seat to avoid the condition of having lubricant getting on the seat and interfering with accurate temperature regulation.

These and other objects of my invention will be better understood as reference is made in the following detailed description to the accompanying drawing, in which—

25 Figure 1 is a view partly in side elevation and partly in longitudinal section through a combination gas cock and oven heat regulator embodying my invention;

Fig. 2 is an enlarged sectional detail of the universally adjustable valve mounting.

The same reference numerals are applied to corresponding parts in these views.

This application is a division of my application Serial No. 47,945, filed November 2, 1935.

35 The present invention has particular reference to the novel construction of the valve indicated generally by the reference numeral 5. This valve regulates the flow of gas from the gas supply manifold 6 to the pipe 7 extending to the oven burner of a gas range. 8 is the body of the oven heat regulator of which the valve 5 forms a part. Gas is supplied to the inlet chamber 9 in the body 8 when the rotor 10 is turned relative to the stator 11, provided preferably as an integral part of the

40 body 8 and communicating, as indicated at 12, with the gas supply manifold 6. The dial 13 is operatively connected with the rotor 10 of the gas cock and with a control shaft 14 which extends through the rotor and stator and has a polygonal

45 body 15 slidably but non-rotatably received in the hole 16 in the center of the valve seat plug 17. The latter is threaded in the body 8, as indicated at 18, for axial adjustment by rotation thereof. The extent of adjustment of the 50 plug 17 away from the valve 5, as will soon appear,

determines the oven temperature to be maintained. In other words, the farther the plug 17 is adjusted to the left, the higher will be the oven temperature maintained. Communication is established between the inlet chamber 9 and outlet chamber 19 through the circumferentially spaced holes 20 in the plug 17 when the valve 5 is off the annular seat 21, and, of course, the size of the flame on the oven burner depends upon the extent the valve is opened. When the valve 10 is closed, enough gas is by-passed from the chamber 9 to the chamber 19 through the passage 22 to keep the oven burner from being extinguished, the flow through the by-pass passage being regulated by the valve 23. The valve 5, as will soon appear, normally tends to move away from the seat 21 under the action of the coiled compression spring 24, and is moved in the opposite direction by an expandable bellows 25 which expands in accordance with the expansion of the fluid medium contained therein, which medium is subjected to the heat in the oven through a flexible capillary tube 26 extending from the bellows 25 to a bulb located in the oven. The bulb, tube and bellows, in other words, form a confining chamber 25 for the thermally responsive medium, and the bellows expands and contracts with the expansion and contraction of the medium so as to operate the valve 5 accordingly. A coiled compression spring 27 bears at one end on a shoulder in the chamber 19 and at the other end on a plate 28 fixed to the movable end of the bellows 25, whereby to return the bellows to its normal contracted size when the fluid medium therein contracts with drop in temperature. The part indicated at 29 as supported on the plate 28 is a compensating thermostat, the function of which is to counteract the effect of extraneous heating of the bellows 25 by the cooking top burners, whereby to avoid objectionable oven temperature drop, as clearly described in the parent application.

It is apparent from the above description that the valve 5 will have a graduating action, that is, it will move closer to the seat 21 to prevent an undesired rise in oven temperature and farther away from the seat to prevent an undesired drop in oven temperature. Accurate parallelism between the valve and seat, needless to say, is important if there is to be close control of temperature and also if the regulator is to repeat its performance accurately innumerable times, as required under normal service conditions. The valve construction provided in accordance with my invention, as will now be described, permits the valve disk 30 to adjust itself universally with

respect to its stem 31 by virtue of a ball and socket mounting 32-33, so that the disk 30 can adapt itself nicely to the seat 21 instead of being dependent for such accurate relationship upon accurate mounting and guiding of the valve stem 31 with relation to the seat 21. It will be seen that the stem 31 works in a guide 34 provided by an axial bore in the end of the control shaft 14. Now, of course, the shaft 14 is turned back and forth by means of the dial 13, and there will be a certain amount of relative rotation thereof with respect to the stem 31. If it were not for the capacity of the valve disk 30 to shift its position with respect to the stem 31 into parallelism with the valve seat, the valve disk would not remain parallel to the seat unless its stem were very accurately guided in relation to the seat. The hemispherical portion 32 of the ball and socket mounting 32-33 provides a flat annular shoulder 35 on the back thereof for abutment by the spring 24. A cylindrical hub is provided on the disk 30 concentric with the socket 33, and a graphite impregnated washer 37 bears against the end of the hub and has a snug fit on the valve stem 31 to effect a gas-tight seal. A metallic washer 38 holds the sealing washer in place under the action of a compression spring 39 surrounding the valve stem and abutting the head 40 of a plug which has its stem 41 pressed into a bore in the end of the stem 31. Obviously the valve disk 30 can adjust itself relative to the stem, as indicated by the dotted line position shown in Fig. 2, and will therefore seat nicely on the valve seat 21 regardless of any slight discrepancy in the relationship of the stem 31 out of normality relative to the valve seat 21. In other words, the valve always opens and closes in parallel relation to the seat. The washer 37 furthermore always maintains a good seal regardless of slight inclination of the valve disk one way or another with respect to the valve stem.

The plug 17 will, of course, be supplied with lubricant at the time the device is assembled, so as to insure smooth and easy turning of the plug with the dial 13. Now, some of this lubricant when expelled from the threads as the plug is entered would be apt to run over the valve seat 21 and interfere with accurate temperature regulation. It is for that reason I provide the annular groove 42 in the plug 17 directly behind the seat 21, between the seat and the larger threaded body portion of the plug. Any oil flowing from the ends of the threads 18 will be caught in this annular groove and conducted to the lower side of the plug instead of being permitted to flow onto the valve seat surface. The seat is of triangular cross-section with the apex of the triangle forming a sharply defined valve seat surface for engagement by the annular rim portion of the valve disk 30. The groove 42 is located directly behind the triangular valve seat portion with one side of the groove formed by a portion of the base of the triangle and the other side of the groove formed by the end of the relatively larger body portion of the plug 17.

It is believed the foregoing description conveys a good understanding of the objects and advantages of my invention. While I have illustrated the improved valve construction as applied to a gas valve, it should, of course, be apparent that certain of the features of the invention are applicable to valves generally. The appended claims have been drawn with a view to covering all legitimate modifications and adaptations.

I claim:

1. The combination in a casing, of a poppet valve, a valve seat, a valve stem guide substantially normal to the plane of said seat, a valve stem reciprocable therein and having an enlarged spheroidal shaped portion slidably received in a socket provided therefor in said valve, whereby said valve is supported on the stem and universally tilttable relative thereto so as to adjust itself into parallelism to the valve seat, means for yieldably holding the valve in engagement with said spheroidal shaped portion, the valve having an enlarged hollow hub portion coaxial with the socket therein and projecting from the opposite side of the valve, and sealing means acting between the valve stem and said hub portion yieldable so as to permit tilting of the valve relative to the stem without disrupting the seal. 5

2. A valve structure as set forth in claim 1, wherein said enlarged spheroidal shaped portion on the valve stem is of substantially hemispherical form, whereby to provide an annular shoulder on the side thereof opposite the spheroidal surface, the valve including spring means acting between said guide and said shoulder normally urging the valve stem in one direction to open 20 25 the valve.

3. In a valve, the combination of a body having a substantially horizontal internally threaded bore, an externally threaded valve seat member threaded in said bore terminating in a valve 30 seat surface in a substantially vertical plane, the valve seat member being arranged to be axially adjusted by rotation thereof, and a poppet valve movable toward and away from said seat, said valve seat member having an annular external 35 groove provided therein in a substantially vertical plane between the end of the threaded portion thereof and the valve seat surface on its end, said groove being wholly inside the external circumference of the threaded portion of said valve 40 seat member and arranged to catch any foreign matter gathering on the outside of said valve seat member near the seating surface on its end, whereby to retain or conduct the same away and prevent contamination thereby of the seating 45 surface.

4. In a gas valve of the character described comprising a casing having a substantially horizontal bore provided therein, at least a portion of which is threaded, a valve seat bushing adjustably mounted in the threaded portion of said bore, the interengaging threads of the bore and bushing having lubricant therebetween to facilitate adjustment of said bushing, and a projecting annular valve seat surface on one end 55 of said bushing, the valve seat end of said bushing being of reduced diameter externally and said reduced portion having an annular lubricant conducting groove provided externally therein between the threaded periphery of the bushing and the valve seat surface arranged to intercept lubricant gathering on the seat end of the bushing and conduct it around the bushing to the bottom thereof so as to prevent contamination of the seat surface. 60 65

5. The combination in a casing, of a poppet valve, a valve seat, a valve stem guide substantially normal to the plane of said seat, a valve stem reciprocable therein and having an enlarged spheroidal-shaped portion slidably received in a socket provided therefor in said valve, whereby said valve is supported on the stem and universally tilttable relative thereto so as to adjust itself into parallelism to the valve seat, means for yieldably holding the valve in engagement 70 75

with said spheroidal-shaped portion, comprising an enlarged hollow hub portion on the valve coaxial with the socket therein and projecting from the opposite side of the valve and terminating in a flat end surface, and one or more yieldable washers having sealing engagement with the valve stem centrally and having sealing engage-

ment marginally thereof on the flat end of said hub portion, and spring means on said stem urging said washers into engagement with the hub portion whereby to permit tilting of the valve relative to the stem without disturbing the seal. 5

JOHN H. GRAYSON.
